UNITED STATES PATENT OFFICE.

ROBERT LOWRY, OF NASHVILLE, TENNESSEE.

DESIGN FOR NEWEL-POST.

Specification forming part of Design No. 6,281, dated December 3, 1872.

To all whom it may concern:

Be it known that I, ROBERT LOWRY, of Nashville, in the county of Davidson and State of Tennessee, have invented and discovered a new and original design, shape, or configuration for Newel-Posts, of which the following is a full, clear, and exact description or specification, reference being had to the accompanying drawing, which is here made a part of this specification.

Figure 1 in the drawing is a front elevation of the newel-post, showing the configuration, moldings, fillets, curve, &c. Fig. 2 is a cross-section, showing the core under ogee shaft. Fig. 3 is a plan of base of newel-post.

A is the apex-fillet and molding forming the crown; B', a filling-molding; C, a tulip-molding and neck; D, the neck-collar molding. E is an octagon ogee shaft, with the peculiar form shown. H is the core under projections of ogee shaft. This shaft, when turned out, as shown in Fig. 2, at H, and the

ogee shaft dressed down to an octagon, as shown in Fig. 1, forms the graceful curved lines shown at I, which gives peculiar grace and beauty to the newel-post. F is the base-molding, and G is the base of the newel.

I am aware that newels with molding, crown-fillets, &c., and even part octagon, are not new; nor do I claim any of these features. The distinctive character of my design is found in the core under the ogee shaft, the curved lines and drooping points formed by dressing the shaft octagonal, and the octagon ogee shaft.

What I claim as my invention, and desire to secure and protect by Letters Patent, is—

The octagon ogee shaft, in its peculiar form, as constructed, shown, and described.

ROBERT LOWRY.
